United States Patent Office

Des. 208,981
Patented Oct. 24, 1967

208,981

CONTROL CONSOLE

Lindsey B. Hansen, Ogden, Utah, assignor to Hardy Scales Company, Maywood, Calif., a corporation of California

Filed Oct. 26, 1966, Ser. No. 4,438

Term of patent 14 years

(Cl. D26—5)

FIG. 3.

FIG. 2.

FIG. 1.

FIG. 4.

FIG. 1 is a perspective view of a control console showing my new design;

FIG. 2 is a front elevational view thereof;

FIG. 3 is an elevational view taken from one side thereof; and

FIG. 4 is an elevational view taken from the side opposite to that shown in FIG. 3.

I claim:

The ornamental design for a control console, substantially as shown.
